United States Patent Office.

CYRUS ROBERTS AND JOHN A. THROP, OF THREE RIVERS, MICHIGAN.

Letters Patent No. 92,474, dated July 13, 1869.

IMPROVED HORSE-POWER.

The Schedule referred to in these Letters Patent and making part of the same.

To all whom it may concern:

Be it known that we, CYRUS ROBERTS and JOHN A. THROP, of Three Rivers, in the county of St. Joseph, and State of Michigan, have invented certain new and useful Improvements in Horse-Powers, of which the following is a full, clear, and exact description, reference being had to the accompanying drawings, which make part of this specification, and in which—

Figure 1 represents a plan or top view of a horse-power embracing our improvements, when staked in position for operation, and

Figure 2, a vertical longitudinal section of the same, at the line $x x$ of fig. 1.

Our improvements are shown as applied to a "mounted" horse-power, or one which is placed upon wheels for convenience of transportation, but are equally applicable to a "down" power, the objects of our invention being accomplished in either class of machines, when in operation.

The improvements claimed under this patent consist—

First, in a line-shaft, extending outward at the rear of the machine, and connected, by a flexible coupling, with a tumbling-rod, mounted upon a frame hinged thereto, in such manner that the angle of the tumbling-rod with the line-shaft may be varied at pleasure, to answer the requirements of the work; and when not in operation, the frame may be turned up, and used as a rack for supporting the levers, braces, &c., of the horse-power, while being transported.

Second, in the employment of diagonal braces, firmly connecting the bed-plate to the frame, the same being arranged in the direction of the strain to which the former is subjected by the pull of the horses when operating the power, and serving to obviate liability of its working loose or becoming disconnected.

Third, in an improved method of staking the machine to the ground when in operation, whereby both lateral and end-motion of the same are prevented, and the power of the horses effectively exerted, without risk of altering its position, as hereinafter more fully set forth.

In the accompanying drawings, which show a convenient arrangement of parts for carrying out the objects of our invention, A represents the frame of the machine, which, for strength, and convenience of construction and operation, is made in angular form, being narrowest at its front end.

The frame A is supported upon the front and rear axles B B¹, which carry wheels B², the front axle being pivoted to the frame by a king-bolt, b, so as to be turned in either direction while the machine is being moved from place to place.

The gearing by which the line-shaft is rotated is mounted in and supported by an annular metallic bed-plate, C, which is firmly bolted to side sills or beams a, upon the frame.

The bevel-wheel, which gears with the pinion upon the line-shaft, is alone represented, the remainder of the gearing, and the levers to which the horses are attached, not being comprehended in the improvements herein claimed, and being liable to be differently constructed in different machines.

D represents the line-shaft, the front end of which is supported in a bearing, d, pivoted to a hanger, C¹, formed in a piece with or secured to the lower side of the bed-plate. This shaft extends outward at the rear of the machine, and may be set at any angle desired, its rear end being supported in a bearing within, above, or below the axle B¹, as found most convenient.

In addition to being bolted to the frame, as before stated, the bed-plate C is further secured thereto by diagonal braces C², arranged in the line of the strain exerted by the horses when operating the horse-power, they travelling in the direction of the arrows in fig. 1. The braces C² connect the bed-plate and frame rigidly together, and effectually prevent the former from being loosened or displaced.

An angular frame, E, provided with a transverse bolster, E¹, is hinged to the rear of the machine, and may be turned up perpendicularly thereto, or set at any desired angle, its free end resting upon the ground or on a block of suitable height.

The frame E carries the tumbling-rod F, which is connected to a pivoted or flexible coupling, d', upon the end of the line-shaft D, and has its rear end supported by the frame. The tumbling-rod is coupled to the shaft of the machinery to be driven, and, by means of the hinged frame and pivoted coupling described, can be readily adjusted to the height thereof, without altering the level of the bed-plate and frame A.

In order to maintain our horse-power firmly in position upon the ground, when ready for operation, and prevent it from being displaced by the movements of the horses, the following devices are employed:

Sockets h h¹ are secured to the sides of the frame, contiguous to the front and rear axles respectively.

Braces or beams H are inserted in the sockets, having their opposite ends resting upon the ground, and extending in the direction of the movement of the horses, as shown by the arrows, fig. 1.

Stakes h² are firmly driven into the ground, against which the braces H bear when the strain of the horses is brought upon them.

Rods H¹ are hooked to rings or staples upon the frame, and extending in opposite direction to the braces, are connected, by chains H², passing around

pins or rollers h^3 thereon, to stakes h^4 , driven into the ground on opposite sides to the stakes h^2 .

By this arrangement, the four corners of the frame are securely held, the tendency of the movements of the horses being to push against the stakes h^2 , and pull upon stakes h^4 , while, by the relative positions of the braces, an effectual resistance is opposed to the displacement of the machine.

Our improvements are free from complication, may be cheaply constructed, and when in use, are found to accomplish, in a practical and effective manner, the objects of our invention.

What we claim as new, and desire to secure by Letters Patent, is—

1. A line-shaft, extending outward at the rear of a horse-power, supported in a box or bearing below the bed-plate, and a bearing on the rear axle, substantially as described, and for the purpose of enabling the shaft to be hung at any desired angle, as set forth.

2. A hinged rear frame, carrying a tumbling-rod,

connected with the line-shaft by a pivoted coupling, substantially as described, and for the purpose of enabling the angle of the tumbling-rod and line-shaft to be varied, as set forth.

3. The combination of the frame, the bed-plate, and the diagonal braces C^2 , connecting the frame and bed-plate, all constructed for joint operation, substantially as set forth.

4. The combination of the frame, the thrust-brace H , the tension-rod H^1 , the chain H^3 , and the fastening-stakes h^2 h^4 , all constructed for joint operation, substantially as set forth.

5. The combination, substantially as set forth, of a rigid thrust-brace and a flexible tension-brace.
